UNITED STATES PATENT OFFICE.

MARTIN HEMLEB, OF ELIZABETH, NEW JERSEY, ASSIGNOR TO THE SINGER MANUFACTURING COMPANY, A CORPORATION OF NEW JERSEY.

MOTOR ATTACHMENT FOR SWING MACHINES.

Application filed December 21, 1917. Serial No. 208,205.

To all whom it may concern:

Be it known that I, MARTIN HEMLEB, a citizen of the United States, residing at Elizabeth, in the county of Union and State of New Jersey, have invented certain new and useful Improvements in Motor Attachments for Sewing Machines, of which the following is a specification, reference being had therein to the accompanying drawings.

10 This invention relates to motors for sewing machines and to attachments for holding them in driving relation with sewing machines.

In sewing machines provided with a 15 driving motor and adapted to be moved either bodily or about a hinged connection with a table on which they are mounted, it has been found that the motor is liable to be accidentally shifted out of a desirable retracted or inoperative position with the result in drop-head sewing machines that it is liable to strike against the surface of the table and mar its appearance. The present invention aims to insure retention of the 20 motor in a desired out-of-the-way position to guard against accidental displacement therefrom and more specifically in drop-head sewing machines to prevent marring of the table on which the drop-head is hinged.

25 In its preferred form the invention is applied to a bracket fixedly secured to the frame of the machine which bracket has hinged sections one of which carries the motor and permits it being moved from a position driving the machine to a position beneath the overhanging arm in which latter position it is retained against accidental displacement by positive mechanical means in the form of a spring latch.

30 In the accompanying drawings illustrating a preferred embodiment of the invention Fig. 1 shows a rear side elevation of the sewing machine with the motor supported on a bracket in a position beneath the overhanging arm, and in dotted lines the motor in driving relation with the machine. Fig. 2 represents a sewing machine in cross-section with the motor in its driving position and looking toward the vertical stand. Fig. 3 shows in detail the specific construction of a spring-latch for holding the motor on its bracket beneath the overhanging arm.

The drop-head of the sewing machine 35 illustrated in the drawing comprises a base

plate 1 from which rises a vertical standard 2 carrying an overhanging arm 3 on the free end of which is the head 4 in which are arranged old and well known parts of the stitch-forming mechanism. A rotary 60 shaft 5 is sustained by the overhanging arm 3 and carries a belt-wheel 6 of old and well known form.

Drop-head sewing machines are usually movably supported on a table so that they 65 may be moved from a normal operating position to an inoperative position beneath the surface of the table. In the accompanying drawings the drop-head is shown hinged at 7 on one side of the bed-plate 1 to the 70 table 8, the opposite side of the bed-plate being supported by a hinged section 9 of the table. The machine may be moved from its normal operative position shown in Fig. 2 to a position beneath the table by swinging 75 it upwardly about the hinge 7 turning the movable section 9 upwardly out of the ways, and then swinging the drop-head down through the opening in the table. It is then generally concealed by a leaf or cover (not shown) hinged at one end of the table and movable so as to close the opening.

The motor 10 having a friction surfaced driving pulley 11 is supported on a bracket having relatively movable sections 12 and 13 the former of which is stationary and is fixed to the vertical standard 2 of the drop-head in a suitable manner as by the screw 14 and the latter of which carries a pin 15 80 loosely received within the aperture in the boss 16 of the stationary section 12. The motor is secured in any suitable manner to the movable section 13 and about the pin 15 as an axis it may be swung either in 85 driving relation with the machine as shown in dotted lines in Fig. 1 or in non-driving position beneath the overhanging arm and out of the way. The stationary section 12 of the bracket has an apertured ear 17 holding one end of a tension spring 18 whose other end is fixed to the motor. By the spring 18 the motor is held in driving relation with the machine when in the dotted line position shown in Fig. 1. When the 90 motor is moved to the solid line position shown in Fig. 1 the spring 18 crosses the axis of the pin 15 and consequently tends to hold the motor back under the overhanging arm. But the tension of the spring 18 110

is not sufficient to hold the motor against accidental displacement from its retracted position and it can not be made heavy enough to hold the motor positively in the 5 desired retracted position without imposing a prohibitively large load upon the motor when it is driving the machine.

In order to positively retain the motor in a retracted position out of driving relation 10 with the machine a latch 19 is pivoted at 20 to the movable section 13 of the bracket and a slot 21 is formed in the boss 16 of the stationary section 12 of the bracket, the parts being so disposed relatively that the toe of 15 the latch 19 seats within the slot or keeper under the impetus of its spring 22 when the motor occupies the retracted position shown in Fig. 1 beneath the overhanging arm. To swing the motor to the driving position 20 shown in dotted lines in Fig. 1 the operator merely has to disengage the latch 19 from the recess or keeper 21.

It will thus be seen that in a very simple 25 inexpensive and efficient fashion I have provided means for positively retaining the driving motor of a sewing machine when shifted to an out-of-the-way position against accidental displacement and preventing the supporting table of drop-head machines being 30 marred.

The usual method of arranging the parts in a drop-head sewing machine is, as illustrated in the drawings, to hinge the rear side of the cloth-plate 1 to the table 8 and to 35 hinge a section 9 of the table so as to support the front side of the cloth-plate. To drop the head of this type of machine, it is first swung rearwardly, then the hinged section 9 of the table is swung upwardly and 40 forwardly out of the way, then the head is swung down beneath the table-top, and finally the section 9 and cover-leaf section (not shown) are closed over the machine. In drop-head cabinet construction standard 45 form and arrangement like that illustrated in the drawing has been reached. It is neither desirable nor advisable to depart from the settled construction. It has marketable qualities and advantages demanded 50 by the trade. It cannot be altered without being rendered objectionable in one way or another. To such settled drop-head construction applicant's invention is applied. It will be seen that the initial step in the operation 55 of lowering a drop-head machine is to swing the head rearwardly to permit shifting the hinged section 9 of the table out of the way. In this initial step, the tension of spring 18 (which it will be remembered 60 crosses to the front of the axis of pin 15 when the motor is positioned under the arm) is not enough to resist the force of gravity pulling the motor down about the pivot 15 and the motor is likely to strike 65 against the top of the table and mar its fin-

ish. Minus the latch, the construction and arrangement of motor-support is commercially unsatisfactory. With the latch this objection is overcome and the device rendered practical. The latch constitutes primarily a means for holding the motor in operative position during the movement of the drop-head to concealed position, but it will be obvious that when the motor is under the arm the latch also guards against accidental displacement thereof whether the head be upright or lowered.

Having thus set forth the nature of the invention, what I claim herein is:—

1. In combination, a table, a sewing machine having a drop-head including a bed-plate and an overhanging arm, a hinge connecting said drop-head and table on one side of the bed-plate, means movable upwardly relative to the table for sustaining the opposite side of the bed-plate and supporting the bed-plate of the head substantially flush with the table whereby the head may be dropped beneath the plane of the table, a rotary shaft supported by said arm, a motor, driving connections between said motor and said shaft, a support for said motor attached to the drop-head and having a pivoted section permitting the motor to be swung from an operative driving relation with the rotary shaft to an inoperative position beneath the overhanging arm, means for holding said motor in driving relation with the shaft during the operation of the sewing machine, and positive mechanical means for holding said motor beneath the arm when the drop-head is moved on its hinged connection to the table.

2. In combination, a table, a sewing machine having a drop-head including a bed-plate and an overhanging arm, a hinge connecting said drop-head and table on one side of the bed-plate, means movable upwardly relative to the table for sustaining the opposite side of the bed-plate and supporting the bed-plate of the head substantially flush with the table whereby the head may be dropped beneath the plane of the table, a rotary shaft supported by said arm, a motor, driving connections between said motor and said motor in driving relation with the shaft to the drop-head and having a pivoted section permitting the motor to be swung from an inoperative position beneath the overhanging arm, means for holding said motor in driving relation with the shaft during the operation of the sewing machine, and latching mechanism between the pivoted section and its support for holding said motor beneath the arm when the drop-head is moved on its hinged connection to the table.

3. In combination, a table, a sewing machine arranged to be moved from a normal operative position to an inoperative position beneath the table, a motor, means on

said motor and machine for driving the latter from the former, and supporting means on the machine for sustaining the motor permitting movement of the motor from a driving position to a non-driving position, and means for locking the motor against displacement in any direction from non-driving position.

4. In combination, a table, a sewing machine arranged to be moved from a normal operative position to an inoperative position beneath the table, a motor, means on said motor and machine for driving the latter from the former, and supporting means on the machine for sustaining the motor permitting movement of the motor from a driving position to a non-driving position, and a spring latching mechanism on said supporting means for locking the motor in a non-driving position.

5. In combination, a sewing machine, a motor for driving the machine, and a bracket sustained by the machine and supporting the motor, said bracket having relatively movable sections one of which is provided with a keeper element, at latch mounted upon and movable relatively to the other of

said sections and adapted to cooperate with the keeper element to lock the motor in a desired position.

6. In combination, a sewing machine, a motor for driving the machine, and a bracket sustained by the machine and supporting the motor, said bracket having sections hinged to swing relatively to one another about one axis only, one of said sections being provided with a keeper element and the other carrying a movable latch adapted to cooperate with the keeper element to lock the motor in a desired position.

7. In combination, a sewing machine including a work-support and an overhanging arm, a motor for driving the machine, a support for the motor secured to the overhanging arm, means on the motor-support allowing the motor to be moved either to operative driving position at one side of the arm or to inoperative position beneath the arm, and locking means on the support for fixing the motor against displacement in any direction from inoperative position.

In testimony whereof, I have signed my name to this specification.

MARTIN HEMLEB.

Certificate of Correction.

It is hereby certified that in Letters Patent No. 1,433,719, granted October 31, 1922, upon the application of Martin Hemleb, of Elizabeth, New Jersey, for an improvement in "Motor Attachments for Sewing Machines," errors appear in the printed specification requiring correction as follows: Page 1, line 78, for the word "ways" read *way*; page 2, line 98, claim 1, for the misspelled word "realtion" read *relation*, and line 116, claim 2, strike out the words "motor in driving relation with the shaft" and insert *shaft, a support for said motor attached*; page 3, line 26, claim 5, for the word "at" read *a*; and that the said Letters Patent should be read with these corrections therein that the same may conform to the record of the case in the Patent Office.

Signed and sealed this 5th day of December, A. D., 1922.

[SEAL.]

KARL FENNING,
Acting Commissioner of Patents.
